VEST

Larry R. Engelson, New York, N. Y.

Application June 1, 1936, Serial No. 82,685

1 Claim. (Cl. 2—102)

This invention relates to new and useful improvements in apparel and more particularly it pertains to vests, waistcoats and similar men's garments.

5 It is the primary object of the present invention to provide a garment of the afore-mentioned type which may be adjusted to any size by the wearer, thus insuring perfect fitting of the garment under all wearing conditions.

10 Such a garment also has advantages from a merchandizing point of view in that it permits of a merchant carrying a large variety of patterns without unduly burdening his stock as would necessarily result if the same number of patterns 15 were carried in the wide range of sizes necessary to provide a complete stock of sizes within the range.

With the above and other objects in view, reference is had to the accompanying drawing, wherein,

20 Figure 1 is a perspective view of a vest constructed in accordance with the present invention.

Figure 2 is a view in side elevation thereof.

25 Figure 3 is an enlarged fragmentary top plan view partly in section.

Figure 4 is a transverse sectional view taken substantially on the line 4—4 of Figure 2, and;

30 Figure 5 is a detail plan view of the neck strap, the intermediate portion thereof being broken away.

Referring to the drawing by reference characters, the garment comprises two body sections 10. These body sections 10 are preferably of similar 35 construction and each has a lapel 11 associated therewith, the lapel in each case overlying a portion of its respective body section to provide a space 12 between the outer face of the body section and the under or inner face of its respective lapel.

40 The body sections 10 are separate from each other, there being no back or side sections such as generally employed in garments of this type. The body sections are, however, adapted to be secured together to form a garment and this phase of the invention will now be described.

45 It will be noted from the drawing that each body section and its associated lapel terminates at its upper end in a relatively narrow shoulder portion 13. To form a garment suitable for wear, the body sections are connected together at their upper ends by a collar strap 14 which is adjustably connected to the relatively narrow shoulder portion of each body section.

50 Means is employed to provide an adjustable

connection between the neck strap and the body sections, and this means preferably consists of buttons 15.

In the present embodiment of the invention there is one of these buttons 15 secured as at 16 5 to each of the body sections 10 and in each instance, the button 15 passes through a button-hole in the lapel of its respective body section 10. This construction, in addition to providing means for attachment of the collar strap 14 serves to 10 cause the lapels to lie flat upon the body sections at the upper ends thereof.

As illustrated, the collar strap is provided near each of its ends with a series of openings in the form of button holes, and these openings are 15 adapted to receive their respective button 15 when the body sections are secured together to form the garment.

In securing the body sections together to form a garment, the lapels are disconnected with their 20 respective buttons 15 thereby to provide ready access to the space 12 between each body section 10 and its respective lapel 11. The collar strap is now attached by engaging the proper buttonholes over their respective proper buttons 25 to provide a garment of the desired size. After the collar strap has been thus attached, the buttonholes 17 of the lapels are engaged with their respective buttons and the garment is ready for wear. In order to provide a more perfect fit, a 30 conventional adjustable waist strap 20 may be employed.

From the foregoing it will be apparent that the present invention provides a new and improved garment which is so constructed that it may be 35 adjusted to various sizes and lengths and that such result may be accomplished in a simple and easy manner.

Having thus described the invention, what is 40 claimed as new, is:

A vest comprising two separate body sections, a lapel carried by each of said body sections, each of said lapels overlying a portion of its respective body section, a fastening element carried by each of said body sections, the fastening element 45 carried by each of said body sections passing through an opening in the lapel carried thereby, and a removable neck strap for connecting said body sections together, said neck strap having a plurality of openings near each end thereof for 50 engagement with the afore-mentioned fastening elements carried by the body sections with the ends of the neck strap lying between their respective body section and lapel.
